Primary Examiner — George J Ulsh*Assistant Examiner* — Andrea Marie McKay(57) **CLAIM**

The ornamental design for an air conditioner rack as shown and described.

DESCRIPTION

FIG. 1 is a top, front and right side perspective view of an air conditioner rack showing my new design;

FIG. 2 is a top, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1; and,

FIG. 11 is an enlarged view of portion 11 in FIG. 2.

The evenly dashed broken lines in the drawings illustrate portions of the air conditioner rack which form no part of the claimed design.

The unevenly dashed broken lines illustrate the boundary of the enlarged views and form no part of the claimed design.
